UNITED STATES PATENT OFFICE.

ANDREW NOVOMIROFF, OF NEW YORK, N. Y.

COMBINATION-TABLE.

1,322,132.

Specification of Letters Patent.

Patented Nov. 18, 1919.

Application filed May 7, 1919. Serial No. 295,336.

To all whom it may concern:

Be it known that I, ANDREW NOVOMIROFF, a citizen of Russia, residing at New York, county of New York, and State of New York, 5 have invented certain new and useful Improvements in Combination-Tables, of which the following is a specification.

This invention relates to improvements in combination furniture and has for its principal object to provide a device comprising a table beneath which chairs may be stored when not in use.

Another object of the invention resides in the provision of a table having drop leaves which when not in use may be lowered to partially inclose the chairs.

A further object of the invention is to provide an operating means by which the chairs may be drawn into the space beneath 20 the table and a locking means for retaining the table leaves in elevated position.

With these and other objects, which will become apparent as the description progresses, the invention consists in the novel 25 construction, combination and arrangement of parts as will be fully set forth in the following specification, claimed and illustrated in the accompanying drawing in which,

30 Figure 1 is a plan view of the table base.
Fig. 2 is a bottom plan view of the table top.

Fig. 3 is an enlarged fragmentary sectional view through the table, illustrating 35 the operating mechanism in detail.

Fig. 4 is a fragmentary sectional view of the table, showing one of the chairs partially moved to closed position, and

40 Fig. 5 is a fragmentary sectional view of the table illustrating one of the leaves partially lowered.

Referring to the drawings in detail the 45 numeral 1 designates the floor plate on base of the table having attached thereto the guide tracks 2 which are arranged in pairs and have their inner ends connected by a bridge piece 3. Each bridge piece is formed with a central enlargement 4 having a bore formed therein through which a shaft 5 extends. Each shaft 5 is provided at its inner end with a bevel pinion 6 and at its outer end with a screw threaded extension 7.

50 Slidably mounted in each of the tracks 2 is a guide 8 which is formed at the lower 55 end of a bracket 9 attached to the under

side of a chair 10. Each chair is provided with a back 11 which is pivoted, as at 12, to permit the same to swing as indicated in the dotted lines in Fig. 3. Formed on the bracket 9 near its lower end is a forwardly 60 extending ear 13 to which is connected a yoke 14 having at its extreme forward end an internally screw threaded socket 15 for the reception of the extension 7 previously described. It will thus be seen that when 65 the shaft 5 is rotated the chairs will be moved either into or out of the space beneath the table top and base.

In order to provide an operating means for the shafts 5 a vertically extending drive 70 shaft 16 is arranged centrally of the table and is provided adjacent its lower end with a bevel gear 17 which meshes with pinions 6. A bevel pinion 18 is secured to the shaft 16 near its upper end and meshes with a bevel 75 pinion 19 which is secured to the horizontal shaft 20. This shaft 20 is journaled in bearings 21 attached to the under side of the table top 22 and is provided at its outer end with a hand wheel 23 by means of which 80 the movements of the shafts 20, 16 and 5 are controlled.

The table 22 is provided with leaves 24 which are attached thereto by means of 85 hinges 25 and these leaves are held in their elevated position by means of legs 26 which are hinged as at 27 to said leaves. In order to limit outward movements of the legs, 90 links 28 are provided and will prevent the legs from moving outwardly beyond the vertical.

In order that the leaves may be secured in elevated position and held against accidental displacement, a plurality of sliding bolts 29 are provided. These bolts are arranged in pairs and one pair of said bolts is provided on its under side with a plurality of rack teeth 30 which are designed for co-operation with the pinions 31 mounted on an operating shaft 32. A hand wheel 33 is attached to the shaft 32 and is designed to control the movements of the shaft and the bolts. In order that the opposite pair of bolts may be moved simultaneously with the first pair, each bolt is provided on its inner 105 end with an offset rack bar 34. These rack bars are slidable through brackets 35 in which the pinions 36 are rotatably mounted. From the drawing it will be readily seen that the pinions 36 mesh with the rack bars 110

34, and consequently any movement imparted to one of said bars will cause the other bars to move simultaneously.

From the foregoing it will be evident that

5 the table may be placed in condition for use by raising the leaves 24 and locking them by operating the hand wheel 33. The chairs may then be moved into position by rotating hand wheel 23. When it is desired to
10 discontinue further use of the table, the chairs may be closed by lowering their backs and the turning of the hand wheel 23 after which, the leaves may be returned to folded position.

15 While in the foregoing there has been shown and described the preferred embodiment of this invention it is to be understood that certain minor changes in the construction, combination and arrangement of parts

may be resorted to without departing from 20 the spirit and scope of the invention as claimed.

What is claimed is,

In combination with a table top having leaves hinged thereto, a plurality of sliding 25 bolts arranged in pairs, each having a plurality of rack teeth on the underside, an operating shaft, pinions on said shaft engaging the teeth of said bolts, an operating hand wheel on said shaft, an offset rack 30 bar on the inner end of each of said bolts, brackets through which these rack bars slide, pinions mounted in said brackets and meshing with said rack bars, for moving the pairs of bolts simultaneously.

In testimony whereof I have affixed my signature:

ANDREW NOVOMIROFF.
